UNITED STATES PATENT OFFICE.

FREDERICK E. KELSEY, OF NEW YORK, N. Y.

CIGAR-WRAPPER-CUTTING MACHINE.

SPECIFICATION forming part of Letters Patent No. 726,540, dated April 28, 1903.

Application filed July 28, 1902. Serial No. 117,229. (No model.)

To all whom it may concern:

Be it known that I, FREDERICK E. KELSEY, a citizen of the United States, and a resident of New York city, borough of Manhattan, county 5 and State of New York, have invented certain new and useful Improvements in Cigar-Wrapper-Cutting Machines, of which the following is a specification, taken in connection with the accompanying drawings, which form a 10 part of the same.

This invention relates to cigar-wrapper-cutting machines for cutting cigar-wrappers and for applying the same in making cigars.

In the accompanying drawings, in which 15 the same reference-letters refer to similar parts in the several figures, Figure 1 is a vertical sectional view showing an embodiment of my invention. Fig. 2 is a perspective view of the same, parts being broken away.

20 The rigid frame A is formed with a bracket B at one end of the same, in which the arm-pivots C and D are secured. These pivots engage the vertical portion E of the arm F and allow this arm to move about a vertical 25 axis. The roller G is shown as pivoted, by means of the pin H, in the outer end of the arm, and the handle I is secured at this point, by means of which the arm may be readily operated.

30 The wheel K is mounted in the arm adjacent the arm-pivots, this wheel being rotatably mounted in the wheel-block J, which may be rigidly clamped in the arm by the screw M. This wheel-block may be 35 vertically adjusted to suit the requirements of the operation of the machine, the adjusting-screw L being shown for this purpose. This screw, which is provided with a suitable lock-nut indicated, engages the upper end of the 40 wheel-block, as is indicated in Fig. 1.

At the forward end of the frame the suction rolling-table N is rigidly secured, this table being formed with a suitable opening O. The suction-box P is supported in this 45 opening by the support Q, which secures this suction-box rigidly to the table. This suction-box is provided at its upper surface with the perforated suction-plate R, which may have any desired shape suitable for a cigar- 50 wrapper, and by exhausting the air from the suction-box by means of the pipe indicated the wrapper may be held firmly in position

upon the suction-plate, as is well known in this art.

The self-adjusting cutting-die S is mounted 55 in the opening O to move vertically about the suction-box P, this vertical movement being effected by the die-elevating mechanism, which operates to elevate the die when the roller or cutting member passes over the 60 die, so that said die is positively moved relatively to the table, and thereby caused to project beyond the table as the roller moves over the die. The die is mounted in the lever V, which is formed with a yoke, as indicated, to extend around the die, and the die-pivots W are secured in this yoke to support the die and at the same time allow it to swivel about these pivots. This lever turns about the bearings U in the frame, and its rear end 65 T, which is provided with a cam portion to be engaged by the wheel, is guided between the vertical guides Y. When this cam portion of the lever is engaged by the wheel, as indicated in Fig. 1, it is pressed downward 70 thereby and, thereupon elevates the die into operative engagement with the roller. As soon as the wheel passes out of contact with the lever the spring Z operates to depress the cutting-die below the surface of the table. 75 The inclines or buffers X are rigidly secured to the cutting-die at either end of the same and extend substantially tangent to the cutting edge of the die.

In operating this cigar-wrapper-cutting machine the tobacco-leaf from which a wrapper is to be cut is adjusted over the suction-plate, the parts being in the position indicated in Fig. 2. When the leaf has been properly adjusted, the suction is operated and the leaf 85 is held down firmly upon the suction-plate. The roller is then moved across the table by the handle I, and as the wheel engages the lever the swiveling cutting-die is raised above the level of the suction-plate. The roller in 90 its movement comes into contact with the incline X and rides up this incline into engagement with the cutting edge of the die, the incline thereby preventing the cutting edge from being dulled. The roller as it moves 95 across the die cuts the wrapper accurately, the die being self-adjusting by means of its swiveling bearings, so that both sides of the die are always brought into proper contact 100

with the roller for cutting the wrapper. During this time it will be seen that the cutting-die is held up in contact with the roller, and, furthermore, the force with which these two parts are brought together may be adjusted by adjusting the position of the wheel K in the arm F, which carries the roller. The roller passes over the incline X at the opposite end of the die, and thereupon the spring 10 Z operates to depress the die below the surface of the suction-plate. The outer portions of the leaf may then be removed from the table and the cut wrapper rolled upon a bunch to produce a finished cigar in the ordinary way.

15 Many modifications may be made in this device by those familiar with the art. Parts of the same may be employed without using all of this cigar-machine, and, furthermore, portions may be employed in connection with 20 other devices in this art without departing from the spirit of this invention. I do not, therefore, wish to be limited to the disclosure which I have made in this case; but

What I claim as new, and what I desire to 25 secure by Letters Patent, is set forth in the appended claims:

1. In a cigar-wrapper-cutting machine, a table formed with an opening, a suction-plate mounted in said opening, a lever formed with 30 a yoke, a cutting-die swivelingly mounted in said yoke within said opening, inclines secured to said die substantially tangent to the cutting edge of the same, a pivoted arm, a roller mounted in said arm to coöperate with 35 said die, a wheel adjustably mounted in said arm to coöperate with a cam portion of said lever to elevate said die above said suction-plate as said roller passes over the same.

2. In a cigar-wrapper-cutting machine, a 40 suction rolling-table, a suction-plate mounted in an opening in said table, a cutting-die mounted in said opening around said suction-plate, inclines secured to said die at either end of the same, a lever pivoted to said die at 45 either end of the same, and an arm carrying a roller to coöperate with said die, said arm having means to engage said lever to elevate said die when said roller passes over the same.

3. In a cigar-wrapper-cutting machine, a 50 table formed with an opening, a suction-plate mounted in said opening, a cutting-die, die-elevating means in which said die is swivelingly mounted, a roller mounted to coöperate with said die to elevate said die as it passes 55 over the same.

4. In a cigar-wrapper-cutting machine, a 60 suction-plate, a cutting-die surrounding said suction-plate, die-elevating means in which said die is mounted, a roller mounted to coöperate with said die and to elevate said die when it passes over the same.

5. In a cigar-wrapper-cutting machine, a

rolling-table, a suction-plate mounted in an opening in said table, a swiveling cutting-die mounted in said opening, a roller to coöperate with said die and means to positively elevate said die as said roller passes over the same.

6. In a cigar-wrapper-cutting machine, a 65 rolling-table formed with an opening, a suction-plate and a cutting-die mounted in said opening, a roller coöoperating with said die and means to positively elevate said die as said roller passes over the same.

7. In a cigar-wrapper-cutting machine, a 70 table formed with an opening therein, a suction-plate and cutting-die mounted in said opening, a cutting member coöperating with said die and means to positively elevate said die as said cutting member engages the same.

8. In a cigar-wrapper-cutting machine, a 75 table formed with an opening therein, a cutting-die mounted in said opening, a roller coöperating with said cutting-die and means to positively move said die relatively to said table as said roller passes over the same.

9. In a cigar-wrapper-cutting machine, a suction-plate, a cutting-die mounted adjacent 80 said suction-plate, a movable cutting member coöperating with said die and means to positively move said cutting-die relatively to said suction-plate as said cutting member moves into engagement with the same.

10. In a cigar-wrapper-cutting machine, a cutting-die, a roller to coöperate with said cutting-die and to engage the same simultaneously at several points and a yoke in which 85 said cutting-die is swivelingly mounted.

11. In a cigar-wrapper-cutting machine, a cutting-die, inclines secured to said cutting-die extending substantially tangent to the cutting edge of the same, a cutting-roll to coöperate with said die, said roll coming into contact with said inclines as it engages said die.

12. In a cigar-wrapper-cutting machine, a 90 die, a roller to coöperate with said die and an incline secured to said die to guide said roller as it comes into engagement with the same.

13. In a cigar-wrapper-cutting machine, a 95 support, a self-adjusting cutting-die movably mounted on said support and a coöoperating roll movable with respect to said support to engage the various portions of said die.

14. In a cigar-wrapper-cutting machine, a 100 support, a self-adjusting cutting-die movably mounted on said support and a coöoperating cutting member movable with respect to said support to engage the various portions of said die.
